INVENTOR:

C. Dornier

UNITED STATES PATENT OFFICE.

CLAUDIUS DORNIER, OF FRIEDRICHSHAFEN-ON-THE-BODENSEE, GERMANY, ASSIGNOR
TO THE FIRM DORNIER METALLBAUTEN GESELLSCHAFT MIT BESCHRÄNKTER
HAFTUNG, OF FRIEDRICHSHAFEN, GERMANY.

CARRIAGE FOR FLYING MACHINES.

Application filed April 2, 1923. Serial No. 629,412.

To all whom it may concern:

Be it known that I, CLAUDIUS DORNIER, a citizen of Germany, residing at Friedrichshafen-on-the-Bodensee, Germany, have invented certain new and useful Improvements in Carriages for Flying Machines, of which the following is a specification.

My invention relates to flying machines and more particularly to the landing gear of large or giant-flying machines. It is an object of my invention to improve the strength of such landing gear and the stability of the machine during starting and landing.

15 The landing gear of flying machines as hitherto constructed comprises a plurality of parallel wheels designed to uniformly and in common support the machine. Landing gear of this kind, besides possessing a considerable weight, is liable to be damaged under the action of the bending stresses arising during the landing of the machine. On uneven ground the machine further has a tendency to reverse when starting, according as 20 the wheels on one side run on a higher or lower level than those on the other side, which are under the same load.

25 It is an object of my invention to obviate that drawback. I attain this end by means

30 of a landing gear having a comparatively large starting wheel arranged directly below the hull or body in the plane of symmetry of the hull and is apt to carry substantially alone the entire weight of the machine. As the arrangement may easily be so devised that the starting wheel lies at least approximately below the mass centre of the entire machine and at a short distance therefrom it may at the same time form 35 the main support for the machine. In order to maintain transverse stability light auxiliary wheels or runners are arranged near the ends of streamlined outriggers extending laterally of the starting wheel, such auxiliary 40 wheels or runners being, however, designed to take up but a small part of the total weight.

45 I prefer locating the starting wheel in a sort of casing at the bottom of the hull or body and which is practically integral.

In the drawings affixed to this specifica-

tion and forming part thereof, a flying machine embodying my invention is illustrated diagrammatically by way of example. In the drawings

55

Figure 1 is a front view, and

Figure 2 is a side view.

Referring to the drawings, *a* is the hull, *b* is the supporting plane, *c* is the strong and large supporting wheel, located in a casing *d* formed below the centre of gravity of the machine and offering a space of about semi-circular shape open at the bottom of the casing. The wheel axis is resiliently supported in the side walls of the casing. Rigid outriggers *e* extending on either side of the casing *d* and wheel *c* have fixed to their ends small wheels or runners *f*, which mainly serve as stabilizing members in case that the machine, while starting or landing, should 60 be inclined to one side, and are resiliently connected with the outriggers. Preferably these auxiliary wheels or runners are arranged to touch the ground before the supporting wheel *c* comes in contact therewith.

I wish it to be understood that I do not desire to be limited to the exact details of construction shown and described, for obvious modifications will occur to a person skilled in the art.

80

I claim:

1. Flying machine comprising in combination, a hull, a main bearing plane substantially flush with the upper surface of said hull, a wheel mount forming part of and extending downwards from the bottom portion of said hull, a wheel supported in said wheel mount in the longitudinal axis of said hull and a stump wing or auxiliary bearing plane extending on either side of said wheel mount.

2. Flying machine comprising in combination, a hull, a main bearing plane substantially flush with the upper surface of said hull, a wheel mount forming part of and extending downwards from the bottom portion of said hull, a wheel supported in said wheel mount in the longitudinal axis of said hull, a stump wing or auxiliary bearing plane extending on either side of said wheel mount and supporting means at the outer end of each stump wing.

3. Flying machine comprising in combination, a hull, a main bearing plane substantially flush with the upper surface of said hull, a wheel mount forming part of and extending downwards from the bottom portion of said hull, a wheel supported in said wheel mount in the longitudinal axis of said hull,

a stump wing or auxiliary bearing plane extending on either side of said wheel mount and resiliently mounted runners at the outer 10 end of each stump wing.

In testimony whereof I affix my signature.

CLAUDIUS DORNIER.
